[57] CLAIM

The ornamental design for a spinning toy, as shown and described.

DESCRIPTION

FIG. 1 is a front perspective view of a spinning toy showing my new design, the balls shown in broken lines for illustrative purposes only and from no part of the claim;

FIG. 2 is a top plan view thereof;

FIG. 3 is a front elevational view thereof, the left and right side being a mirror image;

FIG. 4 is a bottom plan view thereof; and,

FIG. 5 is a rear elevational view thereof.
